HANDLE MEMBER FOR A FOLDING POCKET KNIFE OR THE LIKE

Don J. Meserve, Rehoboth, Mass., assignor to Colonial Knife Company, Inc.

Filed July 21, 1970, Ser. No. 24,046

Term of patent 14 years

Int. Cl. D8—03

U.S. Cl. D8—99

FIG. 1

FIG. 2

FIG. 4

FIG. 3

FIG. 5

FIG. 1 is a side elevational view of a handle member for a folding pocket knife showing my new design or the like;

FIG. 2 is a top view thereof;

FIG. 3 is a bottom view thereof;

FIG. 4 is an end view from right end of FIG. 1; and

FIG. 5 is an end view from left end of FIG. 1.

I claim:

The ornamental design for a handle member for a folding pocket knife or the like, substantially as shown.
